UNITED STATES PATENT OFFICE.

HERRMANN A. WULF, OF NORWICH, CONNECTICUT.

SASH-CORD FASTENER.

1,257,438.

Specification of Letters Patent. Patented Feb. 26, 1918.

Application filed September 13, 1917. Serial No. 191,255.

To all whom it may concern:

Be it known that I, HERRMANN A. WULF, a citizen of the United States, residing at Norwich, New London county, Connecticut, have invented certain new and useful Improvements in Sash-Cord Fasteners; and I do declare the following to be a full, clear, and exact description of the invention, such as will enable others skilled in the art to 10 which it appertains to make and use the same.

This invention relates to certain new and useful improvements in a sash cord fastener and it has particular reference to means for 15 anchoring or securing the sash end of the cord to the sash.

One of the principal objects is to provide an improved device of this nature which is simple in design and economical in construction, the parts of which being readily assembled and taken apart without the use of any 20 tools.

Further, the invention resides in a sash cord fastener comprising separable cord 25 clamping members and a connecting slide member having means of attachment to a sash, all of said parts being stamped from sheet metal by a simple operation.

The invention further resides in the features of construction and the arrangements 30 and combinations of parts hereinafter described and claimed, reference being had to the accompanying drawing wherein—

Figure 1 is a perspective view of the improved cord fastener embracing the sash cord;

Fig. 2 is a side elevation of the device showing the same secured in the usual cord groove of a sash;

Fig. 3 is a top plan view of the sash cord fastener; and

Fig. 4 is a vertical section thereof.

Referring more in detail to the drawing, the numeral 1 designates a sash having the 45 usual cord groove 2 and enlarged recess 3 which latter, in former practice, was designed to receive a knot formed on the sash cord to connect the same to the sash. This method of attaching the sash end of the 50 cord has been found unsatisfactory for several reasons, principal among which are the untying and deformation of the knot through wear, which would free the cord of the sash, and the knotted end becoming dislodged.

To overcome these objections and provide 55 a more efficient means of securement for the

sash end of the cord, the present invention has been devised, the same comprising a pair of coöperating and tapering cord clamping members 4 and a connecting and anchoring member 5.

Each clamping member 4 is preferably stamped from sheet metal and comprises a transversely concaved cord embracing seat 6, the side edges of which are bent backwardly into substantially parallel relation to form reinforcing fins or flanges 7. These fins have their longitudinal edges inclined toward one end which gives to the clamping member a taper design.

The anchor plate or member 5 has its ends deflected to conformably fit the recess 3 as depicted in Fig. 2. It comprises a plate formed with a central opening to receive the smaller ends of the clamping members, each 75 end wall of this plate opening being cut to provide spaced seats 8 for the inclined longitudinal edges of the fins to ride on. These seats incline or converge inwardly so that the fins will naturally be held apart against 80 the side walls of the opening.

Between each pair of convergent seats 8, the metal of the plate is turned or bent upwardly and slightly outward, said upturned portion being sharpened to provide prongs 85 or spurs 9 which are designed to be embedded in the sash and thereby serve as an anchor for the fastener.

In practice, the clamping sections or members are placed about the terminal of sash 90 cord 10 with the slide member loosely connecting the same. The spurs 9 are then driven into the wall of the recess 3 and the clamping members wedged firmer into the plate opening. Spurs 11 may also be 95 punched out from the cord seats 6 for entering the cord to provide against the latter slipping in its seats.

The three parts may readily be stamped from sheet metal and shaped in a single operation, the same being so reinforced by the fins that a light device of great strength and durability is thus afforded. Further, the anchoring spurs securely hold the fastener in position against accidental displacement.

What is claimed is:

In a sash cord fastener, a pair of spaced clamping members each consisting of a piece of sheet metal bent to form a transversely concave cord-embracing seat and backwardly bent side fins the longitudinal edges

of which incline toward one end, an anchor plate having an opening to receive the clamping members, the edge of the plate opening being formed with opposing pairs 5 of seats that converge inwardly between the longitudinal edges of the clamping members to thereby brace the fins apart, and an anchoring spur struck upwardly from between the seats of each pair and deflected out-

wardly to engage in the sash at a point intermediate the side fins of the adjacent clamping member.

In testimony whereof I affix my signature in presence of two witnesses.

HERRMANN A. WULF.
